SURFACE SKIMMER FOR SWIMMING POOLS OR THE LIKE

Martin Hoffinger, 382 Garfield Ave.,
West Hempstead, N.Y.

Filed Apr. 27, 1961, Ser. No. 64,921

Term of patent 14 years

(Cl. D91—1)

FIG. 2

FIG. 1 is a perspective view of a surface skimmer for swimming pools or the like showing my new design.

FIG. 2 is a reduced end elevation thereof.

I claim:

The ornamental design for a surface skimmer for swimming pools or the like, as shown.
